UNITED STATES PATENT OFFICE.

SIDNEY A. CLARKE, OF CHICAGO, ILLINOIS.

DESIGN FOR A CURTAIN-RING.

SPECIFICATION forming part of Design No. 22,347, dated April 11, 1893.

Application filed October 3, 1892. Serial No. 447,720. Term of patent 3½ years.

To all whom it may concern:

Be it known that I, SIDNEY A. CLARKE, a citizen of the United States, residing at Chicago, in the county of Cook and State of Illinois, have invented and produced a new and original Design for Curtain-Rings, of which the following is a specification, reference being had to the accompanying drawings, forming a part thereof.

Figure 1 is a perspective view of a curtain-ring, showing my design thereon. Fig. 2 is a vertical sectional view of the ring, these two views being deemed necessary to illustrate my design.

The leading feature of my design consists in a raised beaded trimming which extends around the outer circumference of the ring.

The beaded trimming is indicated by the letter X.

What I claim is—

The design for a curtain-ring, consisting of the ring herein shown and described.

SIDNEY A. CLARKE.
